SOCKET ASSEMBLY

Russell A. Funk, Pleasant Ridge, Mich.

Application April 29, 1940, Serial No. 332,346

5 Claims. (Cl. 173—339)

This invention relates generally to lamp socket assemblies and refers more particularly to improvements in lamp sockets of the type attachable to a suitable mounting member.

One of the principal objects of this invention resides in the provision of a lamp socket assembly composed of a relatively few, simple parts secured together to form a unitary construction and having improved means for readily attaching the socket assembly to a mounting member.

Another object of this invention resides in the provision of a socket assembly having an annular flange insertable into an opening in the mounting member from one side of the latter and having a portion movable into clamping engagement with the opposite side of the mounting member in response to axial movement of the flange into the opening.

A further advantageous feature of this invention consists in the provision of a socket assembly having a continuous annular flange provided with circumferentially spaced portions adapted to be flexed inwardly upon insertion of the flange into the opening in the mounting member from one side of the latter and to return toward their normal positions at the opposite side of the mounting member to cooperate with the latter in effectively securing the socket assembly in place on the mounting member.

In addition to the foregoing, the present invention contemplates a socket assembly of the type set forth in the preceding paragraph wherein the continuous annular flange is provided with diametrically opposed embossed portions adapted to frictionally engage the side edges of the mounting member surrounding the opening and having relatively weak portions between the embossed portions deformable within their elastic limit by the stress placed on the embossed portions to not only permit the embossed portions to flex inwardly as they are advanced through the opening from one side of the mounting member, but to also permit the return movement of the embossed portions at the opposite side of the mounting member to secure the socket assembly in fixed relation to the mounting member.

The foregoing, as well as other objects, will be made more apparent as this description proceeds, especially when considered in connection with the accompanying drawing, wherein:

Figure 1 is a side elevational view of a lamp socket assembly constructed in accordance with this invention;

Figure 2 is an end elevational view of the construction shown in Figure 1;

Figure 3 is a sectional view taken on the plane indicated by the line 3—3 of Figure 2 and showing the socket assembly installed by a mounting member;

Figure 4 is a fragmentary elevational view showing a slightly modified form of socket assembly.

10 Although the present invention may be advantageously employed to secure practically any type of lamp socket to a mounting member, nevertheless, for the purpose of illustrating the present invention, I have shown a socket for use in 15 the single wire circuit commonly employed in connection with motor vehicles. It will be understood, therefore, that each of the several views on the accompanying drawing is enlarged somewhat from actual size to more clearly illustrate the invention.

Upon reference to Figures 1 to 3, inclusive, it will be noted that my improved socket assembly is provided with a tubular casing 10 having one end reduced to form an annular shoulder 11 and having bayonet slots 12 in the opposite end portion for detachably receiving an electric light bulb 13. Slidably mounted in the casing 10 is an insulating block 14 of dielectric material having an electrical contact 15 secured to the center thereof in a position to engage the cooperating electrical contact 16 on the electric light bulb. The contact 15 on the insulating block is yieldably urged into engagement with the contact 16 on the light bulb by means of a coil spring 17 located in the casing 10 with one end abutting the shoulder 11 and with the opposite end abutting the insulating block. Electrical energy is supplied to the bulb by means of an electrical conductor 18 extending from the source of supply 20 through the reduced end of the casing 10 and secured to the electrical contact 15. In accordance with conventional practice, the casing is electrically connected to a common ground with the source of supply and this ground forms the 25 return side of the circuit.

In order to maintain the insulating block 14 in assembled relation with the casing 10 when the bulb is removed from the casing, I provide a pair of shoulders 19 forming an abutment for the insulating block. In the present instance, the shoulders are formed by striking diametrically opposed portions of the casing inwardly so that the free edges of the portions face the reduced end of the casing and engage the end of the insulating block facing the bulb end of the casing.

During assembly, the portions 19 are flexed outwardly by the insulating block as this block is inserted into the casing through the bulb end of the latter. It will, of course, be understood that when the insulating block is moved beyond the portions 19, the latter return to their innermost positions and form stops to prevent disengagement of the insulating block from the casing.

In Figure 3 of the drawing, I have shown the socket assembly installed on a mounting member 20 in the form of a plate having an opening 21 therethrough. In order to secure the socket assembly to the mounting member, I provide a collar 22 having a hub 23 telescopically engaging the casing 10 and permanently secured to the latter. In addition, the collar 22 is formed with a continuous annular flange 24 of greater diameter than the casing 10 and connected to the hub 23 by means of an annular bead 25. The annular flange 24 surrounds the bulb end of the casing 10 and preferably extends beyond the latter end of the casing.

The collar 22 is formed of sheet metal and is preferably subjected to an ironing operation during its fabrication to impart a high degree of resilience thereto. Generally speaking, the annular flange 24 is of less diameter than the diameter of the opening 21 and this flange is inserted into the opening from one side of the mounting member by an axial shifting movement of the socket assembly relative to the mounting member. It will be noted, however, that diametrically opposite sides of the annular flange 24 are embossed to form two pairs of ribs 26 which extend parallel to the axis of the collar from a point adjacent the free end of the flange 24 to a point adjacent the bead 25. The ribs 26 of each pair are spaced from each other circumferentially of the flange 24 and are interconnect-
ed by means of a reinforcing rib 27 extending circumferentially of the flange 24.

Upon reference to Figure 3, it will be noted that each rib 26 has a portion 28 which inclines outwardly from the cylindrical free end portion 29 of the flange and is integrally connected to a second portion 30 which inclines inwardly to a position adjacent the bead 25. The arrangement is such that when the collar is moved with the casing into the opening 21 formed in the mounting member, the portions 28 of the diametrically opposed pairs of ribs frictionally engage the edge of the mounting member surrounding the opening 21. The stresses applied to the annular flange 24 by the frictional engagement of the portions 28 on the ribs 26 with the mounting member serve to flex the rib portions of the flange inwardly and to bow the relatively weak portions 32 of the annular flange outwardly. This stress is increased until the points 33 of the ribs assume positions within the opening 21 in the mounting plate and is gradually relieved as movement of the collar into the opening through the mounting member continues. In this connection, it will be noted that continued movement of the collar 22 in the aforesaid direction engages the portions 30 of the ribs with the edge of the mounting member surrounding the opening 21 and, since the portions 30 are inclined inwardly, it follows that the stress on the ribs is decreased. Of course, decreasing the stress on the ribs permits the relatively weak portions 32 of the flange 24 to return toward their normal positions and to effect an outward movement of the rib portions of the flange 24. The inwardly inclined portions 30 on the ribs 26

are so designed, however, that the stress on the ribs is not entirely relieved and, accordingly, the collar is securely held under tension in the opening 21 through the mounting member.

The embodiment of the invention illustrated in Figure 4 is similar to the construction previously described, with the exception that the annular flange 24' is longitudinally slit at opposite sides of one pair of ribs 26'. The arrangement is such that as the flange 24' is inserted into the opening in the mounting member, the inclined portions 28' on the ribs serve to flex the spring finger inwardly. It, of course, follows that as the flange 24' continues its axial movement through the opening of the mounting member, the inclined portions 30' on the ribs permit the finger to return toward its outermost position. However, the stress is not entirely relieved from the spring finger and, accordingly, the latter is held under tension in the opening of the mounting member. As a result of the above arrangement, the securing action is obtained without deforming the side portions of the flange between the diametrically opposed ribs on the flange and this construction may be preferred in cases where it is desirable to provide a quickly detachable connection between the socket and mounting.

It follows from the foregoing that my improved socket assembly may be readily secured to a mounting member by merely shifting the socket assembly axially relative to the mounting member to locate the annular flange 24 in the opening formed in the mounting member. It will also be observed that the socket is composed of a relatively few number of parts capable of being inexpensively manufactured, assembled and installed.

What I claim as my invention is:

1. In combination with a mounting member having an opening therethrough, a socket assembly, an annular imperforate flange on the socket assembly adapted to extend into the opening in the mounting member from one side of the latter and having diametrically opposed reinforced parts frictionally engageable with the edge of the mounting member surrounding the opening to apply a stress on the flange in an inward direction upon insertion of the flange into the opening in the mounting member, the portions of the flange between the reinforced parts being sufficiently weak to bow outwardly within their elastic limits by the stress applied to the reinforced parts, and said reinforced parts having provision for engaging the opposite side of the mounting member to secure the socket to the latter.

2. In combination with a mounting member having an opening therethrough, a socket assembly, an annular imperforate flange on the socket assembly adapted to extend into the opening in the mounting member from one side of the latter and having diametrically opposed outwardly embossed ribs extending parallel to the axis of the flange, each of the ribs having portions inclined inwardly toward the axis of the flange from a point intermediate the ends of the rib, the inclined portions of the ribs adjacent the free end of the flange adapted to frictionally engage the edge of the mounting member surrounding the opening to flex the ribs inwardly upon axial movement of the flange into the opening of the mounting member and the other portions of the ribs permitting the latter to return toward their

outermost positions whereby the flange is held under tension in engagement with the mounting member.

3. In combination with a mounting member having an opening therethrough, a socket assembly, an annular continuous flange on the socket assembly adapted to extend into the opening in the mounting member from one side of the latter and having two pairs of diametrically opposed ribs extending parallel to the axis of the flange and arranged with the ribs of each pair spaced from each other circumferentially of the flange, the end portions of the ribs adjacent the free end of the flange being inclined to frictionally engage the edge of the mounting member surrounding the opening and flex the ribs inwardly, the opposite end portions of the ribs being inclined in a direction to permit return movement of the ribs toward their normal positions and to secure the flange under tension to 20 the mounting member.

4. In combination with a mounting member having an opening therethrough, a socket assembly, an annular imperforate flange on the socket assembly adapted to extend into the opening in the mounting member from one side of the latter and having diametrically opposed outwardly embossed ribs extending parallel to the axis of the flange, each rib having portions inclined inwardly from a point intermediate the ends there- 25

of, the inclined end portions of the ribs adjacent the free end of the flange being engageable with the edge of the mounting member surrounding the opening to flex the ribs inwardly, the opposite inclined end portions of the ribs being inclined to a lesser degree than the end portions aforesaid to secure the flange under tension to the mounting member.

5. In combination with a mounting member 10 having an opening therethrough, a socket assembly, an annular flange on the socket assembly adapted to extend into the opening in the mounting member from one side of the latter and having diametrically opposed outwardly embossed ribs extending parallel to the axis of the flange, each rib having portions inclined inwardly from a point intermediate the ends thereof, the inclined end portions of the ribs adjacent the free end of the flange being engageable with the edge of the mounting member surrounding the opening to flex the ribs inwardly, the opposite inclined end portions of the ribs being inclined to a lesser degree than the end portions aforesaid to secure the flange under tension to the mounting member, and an annular bead on said flange at the end of the second named inclined portions of the ribs to limit the extent of axial movement of the flange relative to the mounting member.
